UNITED STATES PATENT OFFICE

141,287

DESIGN FOR A WHEEL TRIM OR SIMILAR ARTICLE

George Albert Lyon, Allenhurst, N. J.

Application July 29, 1944, Serial No. 114,616

Term of patent 14 years

(Cl. D14—30)

To all whom it may concern:

Be it known that I, George Albert Lyon, a citizen of the United States and a resident of the village of Allenhurst, in the county of Monmouth and State of New Jersey, have invented a new, original, and ornamental Design for a Wheel Trim or Similar Article, of which the following is a specification, reference being had to the accompanying drawing, forming a part thereof.

On the drawing:

Figure 1 is a side elevational view of the wheel trim of my new design showing it applied to a side of a wheel and tire, the latter being illustrated by dotted lines.

Figure 2 is a profile view showing the cross

sectional contour of my wheel trim, and illustrating it applied to a tire and wheel rim, the latter being likewise shown in dotted lines.

Figure 3 is a fragmentary enlarged profile view, illustrating the cross sectional contour of the wheel trim and corresponding to the upper half trim, as shown in Figure 2.

The wheel trim of my design embodies a hub cap simulating portion A, an annular trim ring portion B, and an outer ornamental bead C.

I claim:

The ornamental design for a wheel trim or similar article, as shown and described.

GEORGE ALBERT LYON.
